UNITED STATES PATENT OFFICE.

AGNES R. ROSSMAN, OF SCOTCH PLAINS, NEW JERSEY.

SLEEPING CAR.

Application filed November 13, 1924. Serial No. 749,577.

To all whom it may concern:

Be it known that I, AGNES R. ROSSMAN, a citizen of the United States, residing at Scotch Plains, county of Union, and State 5 of New Jersey, have invented certain new and useful Improvements in Sleeping Cars, of which the following is a specification.

This invention relates to improvements in railway cars, and has particular reference to 10 an improved sleeping car construction.

An object of the invention is to provide an improved construction of sleeping car wherein the berths are so arranged as to provide toilet accessories for the occupants 15 and enable them to dress and disrobe with considerable more comfort and convenience than in the cars now commonly employed.

Another object is to interpose between two sets of berths a dressing room compartment 20 individual to each set and to divide each compartment into upper and lower sections each having communication with one of the berths of the set to which said compartment is individual.

Still another object is to establish direct communication between each lower berth and the associated section of its compartment so as to avoid the necessity of the occupant of a berth entering the aisle of the car 25 when passing back and forth between his berth and compartment section.

A further object is to provide each upper berth of a set with means, capable of storage within the berth when not in use, which will facilitate entrance to and exit from the berth 30 and which will not obstruct the aisle of the car when said means is not actually being used.

A still further object is to provide a common support for the lower berth curtains and the bunk of the upper berth when said bunk is in its operative position.

The above and other objects will appear more clearly from the following detailed description, when taken in connection with the accompanying drawings, which illustrate a preferred embodiment of the inventive idea.

In the drawings—

Figure 1 is a fragmentary longitudinal section through a railway car showing in side elevation one set of berths and its associated compartment;

Figure 2 is a view similar to Figure 1, showing the berths made up for occupancy,

the associated compartment being shown in 55 vertical longitudinal section;

Figure 3 is a transverse section on the line 3—3 of Figure 2;

Figure 4 is a similar section on the line 4—4 of Figure 1;

Figure 5 is a fragmentary diagrammatic view showing the arrangement of berths and compartments in the car;

Figure 6 is a fragmentary vertical longitudinal section showing the manner of supporting the bunk of the upper berth and the mounting for the curtains of the lower berths;

Figure 7 is a fragmentary perspective view illustrating the means affording access 70 to and exit from the upper berth with said means in its operative position;

Figure 8 is a side elevation showing the means of Figure 7 in its inoperative position;

Figure 9 is an enlarged edge elevation of said means, the dotted lines indicating the operative position thereof; and

Figure 10 is a fragmentary plan view of said means.

Referring more particularly to Figure 5 in which the schematic layout of the car is illustrated, the numeral 11 indicates generally the body of the car having the usual vestibule 12 at one end entering into the 85 aisle 13. Adjacent each end of the car there is provided the usual lounge room 14 with the communicating lavatory 15. The remainder of the car is divided into a plurality of sets of berths, generally indicated by the 90 numeral 16, each set including an upper berth 17 and a lower berth 18 separated by the pivoted bunk 19, which may be of the usual construction commonly employed and which is movable to the inoperative position 95 shown in Figure 4 against the upper side and roof of the car when the berth is not in use. Each of the sets of berths 16 on opposite sides of the aisle 13 at the right hand end of the car, as illustrated in Figure 5, 100 has associated therewith a compartment, generally indicated by the numeral 20, the specific construction of which will presently be described. A second set of berths is arranged next to each of the end sets 16 and then interposed between said second set and the next succeeding set are a pair of compartments 20 each of which is individual to

the next adjacent set of berths. This arrangement of berths and compartments is continued throughout the remainder of the length of the car with the berths at the opposite end arranged as described in connection with the berths adjacent the lounge room 14. The compartment 20 diagonally opposite from the lounge room 14 may, in accordance with the present construction, be 10 provided with a shower bathroom, conventionally illustrated by the numeral 21.

The lower berth 18 of each set is substantially of the same construction as now employed in the Pullman car with the seats 15 therein arranged so that the same may be made up as a bunk. The top section 22 of the back of the seat, when the seat is formed into a bunk, is detached from its operative position and placed under the bunk, as 20 shown in Figures 2 and 3. The end wall 23 of the lower berth of each set adjacent the associated compartment 20 is provided with an opening 24 which is normally closed by a vertically folding door 25 which may be 25 raised to the position shown in Figure 2 and held in such position by a catch 26 so that the occupant of the lower berth may readily enter his compartment 20 through the opening 24 without passing into the 30 aisle of the car. Each compartment 20 is divided into lower and upper sections 27 and 28, respectively, by means of a partition 29 and the lower section of each compartment contain various toilet accessories 35 for the convenience of the occupant of the lower berth. The lower section 27 of the compartment is also provided with a door 30 through which access may be obtained to the compartment from the aisle 13 of the car when the berths are not made up. If 40 desired, the two adjacent compartments 20 may be provided with folding communicating doors 31 which may be locked, if necessary. The upper section 28 of each compartment is provided for the purpose of convenience to the occupant of the associated upper berth 17 and may be made sufficiently large to store luggage or clothing therein when the berth is occupied. Communication 45 may be afforded from the berth to the upper section 28 through a door 32 formed in the wall 23 separating the compartment from its associated set of berths. The upper section 50 may also be provided with doors 34 through which access may be had to the upper section 28 from the aisle 13.

At each end of each set of berths there is arranged a vertical supporting member or standard 35, preferably of hollow construction and capable of receiving therein a curtain roller 36 upon which is wound one section 37 of a flexible curtain of any desired construction employed for the purpose of enclosing the lower berth when the same is occupied. The free or outer end of each

section 37 of the curtain has secured thereto a bar 38, the upper end of which is guided in its movements in a trackway 39 formed upon the under surface and adjacent the outer edge of the pivoted bunk 19, while 70 the lower end of said rod is movable in a groove 40 formed in the floor of the car. Suitable latching devices 41 may be utilized to secure the bars 38 together when the curtain is in its closing position. The upper 75 end of the roller 36, which may be of any desired construction wherein a spring is provided for rolling the curtain section upon said roller, is rotatably mounted in the head 42 of the standard 35, which head is provided with a reduced extension 43 upon which an ornamental knob 44 may be mounted when the bunk of the upper berth is in its inoperative position. These knobs may be replaced by light globes which enclose 80 suitable lights, the wire for which may be extended through the standards 35. When said bunk is lowered to the position shown in Figure 3 the knobs or light globes 44 are removed and the outer edge of the bunk 19 85 is supported upon the head 42 of the standard by providing a suitable opening 45 in the bunk which will receive the reduced extension 43. In order that the bunk may be maintained in its operative position a locking device is provided which consists of a spring pressed bolt 46 carried by the bunk 19 and engageable with the extension 43, as shown in Figure 6. By this construction it 90 will be obvious that the bunk 19 is effectively held in its operative position until such time when the bolts 46 are retracted from engagement with the extensions 43 whereupon said bunk may be swung upwardly to its inoperative position. 95

In accordance with the present invention the upper berth is provided with a guard rail 47 of a height substantially equal to the width of the bunk 19 and including a supporting section or arm 48 from which the curtain 49 may be suspended. This guard rail 47 is pivoted to the outer edge of the bunk 19 at 50 and is braced in its operative position by means of the pivoted links 51, connected respectively to the guard rail and to the bunk, as shown in Figure 3. When not in use the guard rail may be folded upon the top of the bunk 19, as shown in Figure 4, in such manner that when the bunk is in its inoperative position a suitable storage place for the guard rail will be provided. The guard rail is provided intermediate its ends with a swinging gate 52 forming the entrance and exit to the upper berth and preferably depending from this gate is 110 an arm 53 utilized for a purpose which will 115 presently appear.

A ladder is provided for each upper berth to facilitate entrance to and exit from the berth and this ladder is shown as compris- 120 125 130

- ing the inner and outer side members 54 and 55, respectively, connected by a plurality of steps 56 hinged to the side members, as indicated at 57, so that the side members 5 may be folded or collapsed, as shown in Figures 8 and 9, so as not to obstruct the aisle 13 when the ladder is not in actual use. Coil springs 58 may be utilized for the purpose of yieldably maintaining the 10 ladder in its folded condition. When folded the ladder is of such length that the same may be placed upon the bunk 19 between the upper surface thereof and the guard rail 47 and stored in this position. 15 The inner side member 54 has extending upwardly therefrom a pair of straps 59, the upper free ends of which are curved so as to engage over the outer edge of the bunk 19 and thus suspend the ladder in its operative position. With the ladder in the position shown in Figure 8 the steps 56 thereof are disposed vertically and the depending arm 53 of the gate 52 is engaged with the inner surface of the top step. Thus 20 when the gate 52 is swung open the outward movement of the same will cause the arm 53 to force the outer side member 55 and consequently the steps 56 outwardly and downwardly against the tension of the 25 springs 58 to the position shown in Figure 7. Thereupon the occupant of the berth may step upon the ladder and thereby reach the floor of the car. As long as the gate remains open the lower end of the arm 53 30 will engage the top step and maintain the ladder in its operative position. If desired, the occupant of the berth may reach up and close the gate to permit the ladder to restore to its folded position under the influence of the springs 58 so as not to obstruct the aisle. In order to again enter the 35 berth it is only necessary to swing the outer side member outwardly and downwardly and then step upon the ladder to hold it in 40 its operative position until the gate can again be opened.
- What is claimed is:
1. In a sleeping car construction, a plurality of sets of berths, and a plurality of dressing room compartments disposed between adjacent sets of berths and each individual to one of said sets.
  2. In a sleeping car construction, a set of berths, and a compartment at the end of said set and divided into upper and lower sections each individual to one of the berths of the set.
  3. In a sleeping car construction, a plurality of sets of upper and lower berths, and a plurality of compartments disposed between said sets and each individual to one of them, each compartment being divided into upper and lower sections each individual, respectively, to the upper and lower berths of the associated set.
  4. In a sleeping car construction, a plurality of sets of berths, a plurality of dressing room compartments disposed between said sets of berths, and a communicating door between said compartments. 70
  5. In a sleeping car construction, a berth, a compartment arranged adjacent said berth, and doors for said compartment one of which permits access to said compartment from said berth and the other from the aisle of the car. 75
  6. In a sleeping car construction, upper and lower berths, a compartment adjacent said berths and including upper and lower sections associated, respectively, with the upper and lower berths, and doors for each section of said compartment one of which permits access to said section from the associated berth and the other from the aisle of the car. 80
  7. In a sleeping car construction, a berth, a compartment arranged adjacent said berth, a foldable door affording communication between said berth and compartment, and a second door for the compartment permitting access thereto from the aisle of the car. 85
  8. In a sleeping car construction, upper and lower berths, a bunk for said upper berth having a trackway therein, supporting members upon which said bunk rests when in operative position, and curtains for the lower berth normally contained within said supporting members and having portions engageable in said trackway to guide said curtain when moved to positions to enclose said lower berth. 90
  9. In a sleeping car construction, a set of berths, a compartment individual thereto and divided into sections corresponding in number to the number of berths in said set, and means affording access directly from each berth to one of said sections. 100
  10. In a sleeping car construction, a set of berths, a compartment individual thereto and divided into sections corresponding in number to the number of berths in said set, doors through which access may be had directly from each berth to one of said sections, and other doors for the compartment affording access to said sections from the aisle of the car. 110
  11. In a sleeping car construction, a berth including a bunk pivoted to the body of the car, a supporting member arranged at each end of said berth and upon which said bunk rests when the latter is in operative position, and cooperating means between the bunk and supporting members for locking the bunk in its operative position. 120
  12. In a sleeping car construction, a berth including a bunk pivoted to the body of the car, a supporting member arranged at each end of said berth and upon which said 130

bunk rests when the latter is in operative position, and a locking bolt carried by said bunk and engageable with one of the supporting members for retaining said bunk in operative position.

13. In a sleeping car construction, upper and lower berths, a bunk for said upper berth, supporting members upon which said bunk rests when in operative position, curtains for the lower berth normally contained within said supporting members and movable to positions therefrom to enclose said lower berth, and means carried by said bunk for guiding said curtains to said positions.

14. In a sleeping car construction, upper

and lower berths, a bunk for said upper berth pivoted to the body of the car, supporting members upon which said bunk rests when swung to operative position, means carried by said bunk and engageable with said members for locking the bunk in its operative position, curtains for the lower berth contained within said supporting members and movable to positions therefrom to enclose said lower berth, and means carried by said bunk for guiding said curtains to said positions.

In testimony whereof I have affixed my signature.

AGNES R. ROSSMAN.
